CONTINUOUS DEPOSITION OF DRY FELTED STRUCTURES

Clark C. Heritage, Minneapolis, Minn., assignor of one-half to Weyerhaeuser Company, a corporation of Washington, and one-half to Wood Conversion Company, St. Paul, Minn., a corporation of Delaware

Filed Apr. 14, 1950, Ser. No. 156,018

15 Claims. (Cl. 19—156)

The present invention relates to the continuous production of felted fiber products by a dry process, and in particular to the production of one or more continuous webs, and one or more continuous streams of individual felted entities, for example small pads.

The production of air-laid fiber felts by deposition of fibers from suspension in air is attended with difficulties which become more pronounced as the objectives of uniformity and high quality of the felt are increased. Dry vegetable fibers, especially the shorter fibers derived from wood, are kinky and consequently tend to entangle and clot as they encounter each other in air suspension. In attempting to secure a high rate of production in forming air-laid felts, common expedients are to increase the fiber concentration in the air, and to increase the rate of flow of the air suspension. In particular the increased concentration tends to induce flocking. The longer the path of travel of an air suspension, the greater are the opportunities for mutual encounter of fibers and hence of clotting. Also, the impinging of the suspended fibers on conduit walls, both straight runs and turns, enhances the clotting. Thus, the deposition of clots instead of or along with individual fibers leads to poor formation and undesirable inequalities throughout the felt.

The present invention employs apparatus and process for forming felts from air-suspended fibers at a high rate of production, with a minimum of clotting, and with variability in the nature of the felts.

It is a general object of the invention to provide a continuous process of felting to produce either a continuous felted web, or a continuous stream of separate felted entities.

It is a general object of the invention to employ superatmospheric pressure on the felting side of a felting screen, and subatmospheric pressure on the other side of the screen.

It is a general object of the invention to form the fiber felt on a cylindrical screen and thereby provide a convex surface to cooperate with a loop of sheet material which may be employed in the process for one or more functions.

It is also an object of the invention to form felted bodies containing non-fibrous material in finely divided form, by a continuous process involving constancy of proportion in the infed materials, and recirculation of fines which escape from the felt.

Various other and ancillary objects and advantages of the invention will become apparent from the following description and explanation of the presently preferred manner of carrying out the invention, as shown in the accompanying drawings, in which:

Fig. 1 is a diagrammatic layout of the process and apparatus therefor.

Fig. 2 shows a felting cylinder of which the peripheral area is in part blocked off by peripheral non-filtering bands to provide a plurality of parallel strips of felt.

Fig. 3 is a modification of the screen cylinder of Fig. 2 in which the several peripheral screen areas for forming

2

strips are divided by cross-bands of blocked areas thus to divide the strips into a succession of felted entities.

First, there is provided means for continuously forming an air suspension of substantially individualized fibers, which is such a means as to permit the reintroduction of fines which escape through the felt and the felting screen, in order to recycle the fines without accumulating a loss of material. The primary objective is to deliver the suspension to a depositing area, and this may be effected by the positional relation of parts. However, to this end there may be, and preferably is, provided a nozzle-like conduit means for delivering the air suspension, which means may readily be designed to minimize clotting and to deliver a uniform and continuous supply of dispersed fibers to and over a depositing area at which a felt is deposited by filtering the fibers from the air suspension. Then there is employed a rotating cylindrical filtering or felting screen which presents felting screen area substantially exposed in said depositing area, with permissible blocked-off or blank non-filtering area where division of the felt structure is desired, such as division into continuous bands or one stream or more of separate bodies of felts. Associated with the cylindrical screen is means for exerting suction under the screen at an area including the depositing area, to assist in forming the felt on the screen and to collect the fines which pass through the felt and the screen. Before the formed felt on the cylindrical screen has an opportunity to become detached from the screen, means is provided which may be employed to wrap a continuous web of sheet material over the face of the felt to travel with it to a new position where it functions after removal of the felt from the screen.

The means for providing a stream of air containing suspended fibers at superatmospheric pressure may be of numerous kinds. The preferred method is illustrated in Fig. 1. Fibrous material 10, such as pulp laps or other bulk forms of fibrous material to be individualized for dispersion, is fed at a controllable rate into a hopper 11 which leads to a mill 12 of suitable character to disintegrate the supplied fibrous material into a mass of substantially individualized fibers, clotted or not, and in high concentration preferably in the form of a fluff. The mill may be one of conventional type for the purpose, such as a hammer-mill having a cylindrical casing 13, an arcuate portion of which is perforated as indicated at 14, through which portion the disintegrated material is discharged as fiber into a receiver 15. The mill has a co-axial rotor 16 which has vanes or other means such as swinging hammers 17 so arranged that in rotation of the rotor the hammers effect disintegration of the fibrous material 10, and also movement of it through the perforated screen portion 14. Such a mill is commonly associated with means to cause a current of air to flow through it. As shown in the drawings, the receiving chamber 15 is connected tightly over the plate 14 and also connected to the suction side of a blower 20 which discharges through conduit 21 to a cyclone 22. Thus, in operation the fibrous material 10 is disintegrated into a material which may be discharged as a fluff into said cyclone 22 along with vehicular air drawn in whole or in part from the atmosphere at the hopper 11 by action including that of the blower 20.

The cyclone 22 functions to separate air and the fiber or fluff, discharging the air upwardly through a top vent 23 for exhaust. For numerous reasons of economy, part of the air so vented through the top portion 23 may be recycled by way of conduit 24 which leads into the hopper 11. The cyclone 22 is operated so that its bottom portion 25 does not discharge air under pressure, but only the fiber which settles downwardly in its conical base, preferably as a supply of accumulated fiber of variable depth to accommodate irregularities in the feed.

ing of fiber 10 into hopper 11. Beneath the cyclone is an endless conveyer belt 28 which gathers on it fiber 29 as the belt passes under the lower end 25 of the cyclone. Preferably the belt is operated at a controlled rate and is arranged to carry a measured amount of fiber in a given time, thus allowing a reserve supply to be maintained in the bottom 25 of the cyclone. The measured amount may be controlled by regulating the distance between the discharge opening 25 and the conveyer belt 28, and also by regulating the rate of travel of the belt 28.

The arrangement described permits the feed from the conveyer belt 28 of substantially individualized fibers in fluff form at a regular rate for dispersal and delivery to the felting means. The dispersal in air for felting is effected by a final disperser which may be generally of the same type as the primary disperser 13. Modifications, however, are indicated. As a final disperser there is shown a cylindrical casing 30 on a horizontal axis, having an arcuate extent of its periphery, namely about 90°, perforated as a screen 31, through which fibers are urged by operation of the disperser. There is an agitator in the casing, preferably provided as a co-axial rotor 32 which may operate at high speed, and thereby act as a sort of fan or blower to induce a flow of air outwardly through the casing to discharge at superatmospheric pressure through the screen 31. In the event the agitator does not operate as a blower fan, for example when the rotor 32 is merely oscillated, other means may be employed to create the moving current of air, such as a blower, preferably on the intake side of the casing 30. The agitator or rotor 32 carries fixed on radial swinging blades 33 on which there are suitable heads, for example rubber pads 34, which rub the fluff 29 against the inside of the casing 30 to individualize it. The stream of air flowing through the casing carries the individualized fibers away through the ports in plate 31. The mill may be fed laterally, as at one vertical wall of the casing wherein an opening 35 is indicated, or longitudinally or facewise, if means for obtaining the desired flow of air and fluff is provided as mentioned above. Leading to the opening 35 is a hopper 36 open to the atmosphere into which the conveyer belt 28 discharges its load of fluff alongside air drawn into the hopper from the atmosphere by the suction applied thereto, which air enters as a fiber-free portion of the current of air for depositing the fiber.

The peripheral extent of the screen 31 in part predetermines the direction and character of the discharged air-suspension of fiber. The next step is to pass the stream of air and fiber through a screen to form a felt. This place of formation is called herein a depositing area, and its location predetermines the path of a moving screen on which the felt is formed. To assist the deposition, suction is applied under the screen, whereas the air stream in the depositing area is at superatmospheric pressure. The suction capacity is such as to take in all the air constituting the current which carries fibers into the depositing area, in order to prevent escape of fibers and air from the depositing area into the atmosphere. Consequently the area of the screen at which suction is applied includes the entire depositing area within its bounds, and preferably the suction area is greater than the depositing area to draw in atmospheric air as a sort of envelope to house the air suspension.

To these ends, the screen 31 of the final disperser may be placed very close to the depositing area, or be remote from it when suitable means is employed to confine the current of air discharged at the screen 31 and direct it toward or to the depositing area. Because of the wide angle comprehended by the particularly illustrated screen 31, such a confining means is employed in the apparatus of the drawings. Since the distance traversed from the screen to the depositing area is also preferably short, the said confining means is extended as a sort of conduit or nozzle substantially to the depositing area.

On the external face of the disperser 30 is a collecting hood or nozzle 38 having a special construction. It is so formed as to have two diverging horn-like sections, leading to the edges of the perforated plate 31 of the disperser, thus to gather the air suspension coming through screen 31 and narrowing the passageway for it so that the velocity of the discharged suspension increases as it moves away from the screen. By this means clotting is minimized by a tendency to move each fiber faster than each following fiber where there are the side walls of the horns tending to induce clotting. This constriction of the cross-section of the stream is carried to the depositing area where the felt is formed, by the slight taper of the nozzle 38.

The felting means is provided as a cylindrical screen of which a screen periphery 40 moves at a regular rate through a depositing area 41 which in the illustrated embodiment is the orifice of the nozzle 38. The character of the screen may be greatly modified as will be described hereinafter, but for simplification of the description it may be said that the screen 40 in Fig. 1 is entirely perforated without obstructing areas. Thus, on the screen 40 a continuous web may be formed having a width from edge to edge of the orifice of nozzle 38. Such a web is indicated by the numeral 42 as it leaves the depositing area 41 passing under the edge 43 of the nozzle 38.

Associated with the screen 40 is a suction box beneath the depositing area 41 as indicated by the numeral 44. The exposable area of the suction box is preferably variable, and at its maximum lies outside of and encompasses the depositing area, with reference more particularly to the peripheral directions than to the lateral bounds. Arcuate dampers 44a and 44b are adjustable to control the peripheral dimension of the suction opening. The suction box 44 connects by suitable and well-known structure through the axle 45 to a suction conduit 46 leading to the intake of a blower 47 which discharges via conduit 48 to a cyclone 49. The blower 47 is operated so that it tends to draw in more air through the suction box than is supplied to the depositing area 41 through nozzle 38 by the operation of disperser 30, that is, at least all the air in nozzle 38, and preferably an additional amount from the atmosphere. As a result the upper side of the depositing area is at superatmospheric pressure, while the lower side within the cylinder 40 is at subatmospheric pressure. The consequence is that the felting zone itself is at substantially atmospheric pressure, thus to facilitate mechanical construction and operation. By operation to draw in exactly the same amount of air into suction box 44 as flows to the depositing area from the disperser 30, no leakage of suspended fibers from the nozzle to the atmosphere will result. However, such a balance is difficult for practical management and it is therefore preferred that the blower 47 be operated to draw in some air from the atmosphere at the edges of the depositing zone, for example at the edges of the dampers 44a and 44b when positioned to permit it. In the apparatus of the drawing the damper 44a is very close to the nozzle edge 50.

As is well known in producing fiber in the manner described there is a fraction of fines which tends to pass through the felt and the felting screen to enter the exhaust system, comparable to the fibrous content in the white water in making paper on conventional paper-making machines. Since the present apparatus and process may also be operated to include material other than fiber, for example, finely divided resin powder to serve as a bond, later described, some of this powder will also escape. Being frequently the more expensive component of the felt to be formed, such a resin powder must be used in fine subdivision for efficiency. This enhances loss of it into the exhaust, and makes more important the necessity to save the solid entrained com-

ponents of the exhaust. This is effected in the cyclone 49.

Cyclone 49 is of the same general type as the cyclone 22, but its operation is somewhat different. Cyclone 49 vents to the atmosphere by way of conduit 51 at the top, which has an adjustable damper 52. Changing the set of the damper controls the amount of air discharged via vent 51, and compels the remainder to escape through the bottom 53 of the cyclone 49. In operation the cyclone thus effects a separation of the exhaust stream in conduit 48 into at least two portions, one of which is air enriched with the entrained fines from the exhaust. This enriched portion escapes at the bottom 53 of the cyclone and from there it discharges or is conveyed into the hopper 36 alongside the infed fluff 29. Thus, recycling of the fines is effected and there is no loss of material.

The processing of material by the apparatus described calls for a fine adjustment in proportion between fiber and other material, for example, resin powder, and where continuous uniformity in proportion is desired in the final felt 42, it is only necessary to regulate the feed of such materials properly to the disperser. The non-fibrous material may be fed in at hopper 11, or at hopper 36 or at any intermediate location. In continuous operation including the recycling of the fines, the original fed proportion is constantly maintained without adverse effect resulting from the escape of fines through the filtering screen into the exhaust system.

As illustrated the nozzle 38 discharges onto the top of the rotating cylinder 40 so that action of gravity supplements the felting union of the felt to the screen to hold the formed felt 42 onto the cylinder. Before the felt 42 has an opportunity to become detached, a web of sheet material is brought to the face of the felt and combined with it by facial engagement for travel therewith. Thus, as the cylinder rotates, the felt may be held firmly to the cylinder by maintaining contact of the web with the cylinder. The web so introduced may vary in structure and in function. For example, it may merely be a transfer means in the form of an endless belt brought to the cylinder near the top and removed near the bottom at a position where it underlies the felt so that it is merely a vehicle to carry the felt away from the cylinder. The web may be a sheet of paper which is to remain with the formed felt, for example as a liner therefor in some subsequent combination structure. The web may be brought to the face of the felt with active or activatable adhesive applied interfacially, for example by applying such adhesive to the appropriate face of the web.

As shown there is a roll 61 near the top of the cylinder, over which passes a web of material indicated by the numeral 62. The roll may press upon the felt 42 or be spaced from it, serving primarily to position the sheet 62 so that it will wrap around the convex surface below it as presented by the felt on the cylinder. Where the web 62 bears active adhesive, as above mentioned, it is preferred that the roll 61 press upon the felt 42 in order to exert pressure for adhesive engagement at the interface.

At the bottom of the cylinder 40 the relationship of web 62 to felt 42 is such that the web underlies the felt where it may serve as a carrier to support the felt in leaving the cylinder as indicated by the numeral 64. At this point the felt 42 rests on the web or sheet 62 and the two move upwardly away, for example, at an angle for subsequent processing. In the event that the felt 42 adheres to the screen 40, it may be forced away from the screen by air pressure. For this purpose there is shown a pressure chamber 65 fed by compressed air in pipe 66. Chamber 65 opens to the inner face of the screen to blow the felt off the screen, and incidentally clean the screen. Where the felt is continuous as shown in Fig. 1, the felting strength is commonly sufficient to peel the felt from the screen without the necessity to blow it from initial contact position. However, where the felt formed

may be a separate entity, and not a continuous strip, as would result from use of the cylinder of Fig. 3, it is desirable to assist the detachment by use of compressed air. This is especially true when the said felted entity is not adhesively united to sheet 62.

Where the mat 42 is such that it contains a bonding agent, for example in the form of resin powder, which may be activated to thermoset adhesion, it is permitted that the web 62 be a screen through which and through the felt, hot air may be passed to effect heating and bonding rapidly and without delay which would result from the transfer of heat conductively.

In Fig. 2 there is shown a cylinder which may be the same cylinder as shown in Fig. 1. The cylinder has a plurality of wide peripheral filtering bands 68 of the screen material, and between them separating imperforate bands 69 and also imperforate terminal boundary bands 70. The bands 69 and 70 may be of any suitable material, thin or thick. For example, it may be ordinary paper masking tape placed over the perforations of a full cylindrical screen to provide non-felted separations between strips of felt to be formed side-by-side on the bands 68. The bands also may be of rubber, or even metal. Removable masking material over a full screen is preferred to permit varying the pattern.

Fig. 3 shows a cylinder similar to that of Fig. 2 which has terminal imperforate bands 73 and peripheral imperforate masking bands 74, substantially as described with respect to Fig. 2. Additionally there are imperforate cross-bands 75 at spaced intervals over the screen between the circular bands 73 and 74. The bands 75 are preferably equally spaced on the cylinder so that the felt formed between any two adjacent circular bands will consist of a sequence of rectangular pad-like units of the same size. The cross-bands 75 are preferably aligned with each other not only to facilitate subsequent operations on the adjacent series of the felted entities, but also to facilitate operation of the felting machine itself with respect to removing residual fibers which may be deposited on top of the cross-bands 75 as well as on the peripheral bands 73 and 74 of Fig. 3, or the peripheral bands 69 and 70 of Fig. 2.

Although the forces tending to felt the fiber function primarily over the open screen, the felting is not completely so confined and fibers may readily deposit and loosely felt on the imperforate area, or be held partly thereover while engaged in the edge of the tighter felt which is present over the open screen area. Where it is desirable to have well defined edges of the felted strips or units formed, it is possible to clear such residual fibers from the imperforate area before the formed felt becomes facially engaged with the combining sheet 62. One way so to clean the imperforate areas is to blow the fibers therefrom by a suitable gentle current of air not sufficiently strong to break up the desired felted condition at the edges of the primary felt. This is accomplished in one way by placing near but spaced from the periphery of the felt 42 as it leaves the depositing area 41, suitable air jets to blow the fibers away, and preferably a collecting hood over the jets and generally over the area from which the fibers are being removed by the air jet.

In Fig. 1 such mechanism is shown in the form of a hood 80 extending lengthwise of the cylinder just above the surface of the felt at a location between the roll 61 and the nozzle 38. Within the hood are a number of compressed air pipes 81 provided with openings to serve as air jets, which openings are located at positions to blow air onto the imperforate areas of the cylinder. The number of pipes, the locations of the jets and the operation of them, must be varied in accordance with the pattern on the cylinder. The operation of the jets to discharge air is continuous or intermittent, but under control, according to the timing necessary to function only over masked areas. Thus, for the cylinder illus-

trated in Fig. 2 but one of the pipes 81 would function, and it would function continuously because of the continuous passage of the peripheral bands 69 under the corresponding jets. When the cylinder of Fig. 3 is employed rather than the cylinder of Fig. 2, the same jets which function for bands 69 of Fig. 2 may continue to function for the bands 74 of Fig. 3, and additionally the second pipe 81 is made to function along its length as alined cross-bands 75 pass under its jets. To limit the number of pipes in the hood 80, it is seen that the alining of the adjacent cross-bands 75 is preferred to some other arrangement. Simple mechanical means in the nature of an air valve and a control therefor associated with the turning of the cylinder, are readily applicable to control the air. The collecting hood 80 is connected by conduit 83 to the suction side of a small blower 84 which discharges the exhausted material by a conduit 85 into the cyclone 49. This preserves the system from loss of fines in the same manner as described for recycling the fines which pass through the filtering screen. The suction exerted by hood 80 is sufficient to draw air into the hood while the jets are operating to prevent blowing out and loss of fiber and other content.

It is to be understood that the invention is not limited to the illustrative embodiment thereof, and that numerous changes and modifications are contemplated as falling within the scope of the appended claims.

I claim:

1. The method which comprises continuously rotating on a substantially horizontal axis a cylinder of which substantially all of the area is perforated as a screen for filtering fiber as felts thereon from a suspension of fibers in air exposed to said cylinder, continuously drawing air through said cylindrical surface from the exterior to the interior at a stationary localized deposition area which is traversed by the upper part of the surface of the cylinder in its rotation by establishing subatmospheric pressure at said area, directing upon said cylinder at said deposition area a stream of air at superatmospheric pressure containing in suspension material including feltable fibers for felting on said cylinder, the amount of air moving in said stream being at least not greater than the amount of air being drawn through said screen, whereby to limit escape of suspended material from said stream to the atmosphere, dividing the stream of air drawn through said screen into at least two portions of which one portion contains substantially all of the fines of suspended material drawn through said screen, diverting from the air streams recited the air of said portions which is substantially lacking in fines, combining said fines with a continuous supply of the material ultimately dispersed in air for providing the above-mentioned stream which is directed toward said cylinder, applying a continuously moving web of sheet material over the felt already formed on said cylinder and at a location removed from said deposition area for travel of the web with the cylinder in facial engagement with the felt thereon and for supporting the felt, and removing the web and the felt in a generally horizontal direction from the bottom of the cylinder.

2. The method which comprises continuously rotating on a substantially horizontal axis a cylinder of which substantially all of the area is perforated as a screen for filtering fiber as felts thereon from a suspension of fibers in air exposed to said cylinder, continuously drawing air through said cylindrical surface from the exterior to the interior at a stationary localized deposition area at the top side of the cylinder which area is traversed by the surface of the cylinder in its rotation by establishing subatmospheric pressure at said area, directing upon said cylinder at said deposition area a stream of air at superatmospheric pressure containing in suspension material including feltable fibers for felting on said cylinder,

the amount of air moving in said stream being at least not greater than the amount of air being drawn through said screen, whereby to limit escape of suspended material from said stream to the atmosphere, dividing the stream of air drawn through said screen into at least two portions of which one portion contains substantially all of the fines of suspended material drawn through said screen, diverting from the air streams recited the air of said portions which is substantially lacking in fines, combining said fines with a continuous supply of the material ultimately dispersed in air for providing the above-mentioned stream which is directed toward said cylinder, applying a continuously moving web of sheet material over the felt already formed on said cylinder near the top region of the cylinder and at a location removed from said deposition area for travel of the web with the cylinder in facial engagement with the felt thereon, and at a region where said web underlies said felt in position to support the felt removing the felt and web from the cylinder for vehicular support of the felt by the web.

3. The method which comprises continuously feeding material including fibrous material into a continuous stream of air, conducting the mixed air and all said material to a perforated dispersing plate for passage of the air therethrough, continuously distributing all said material over said plate and reducing the fibrous material to substantially individualized fibers, whereby the air passing through said plate carries the material including the individualized fibers into suspension therein, conducting the resulting suspension as a continuous stream at superatmospheric pressure to a stationary localized depositing area which is traversed by the surface of a cylindrical fiber-felting screen rotating on a substantially horizontal axis, applying sub-atmospheric pressure to the underside of said screen at said depositing area in a manner to draw through said screen all the air of said suspension and tending to draw in air from the surrounding atmosphere outside of said cylinder, dividing the resulting stream of air and any fines of suspended material drawn through said screen at the depositing area into at least two portions of which one portion contains substantially all of said fines, diverting from the air streams recited the air of said portions which is substantially lacking in fines, combining said fines with said first-mentioned fibrous material to recycle the fines, and removing the felt from said cylinder.

4. The method which comprises continuously feeding material including fibrous material into a continuous stream of air, conducting the mixed air and all said material to a perforated dispersing plate for passage of the air therethrough, continuously distributing all said material over said plate and reducing the fibrous material to substantially individualized fibers, whereby the air passing through said plate carries the material including the individualized fibers into suspension therein, directing the resulting suspension at superatmospheric pressure at a stationary localized area which is traversed by the surface of a cylindrical fiber-felting screen rotating on a substantially horizontal axis, applying sub-atmospheric pressure to the underside of said screen at said depositing area in a manner to draw through said screen all the air of said suspension and tending to draw in air from the surrounding atmosphere outside of said cylinder, dividing the air and any fines of suspended material drawn through said screen at the depositing area into a stream of air substantially free from said fines and a stream of air enriched in said fines, combining said enriched stream with said first-mentioned material to recycle the fines, diverting the other stream from the remaining recited streams, and removing the felt from the cylinder.

5. The method which comprises continuously feeding material including fibrous material into a continuous

stream of air, conducting the mixed air and all said material to a perforated dispersing plate for passage of the air therethrough, continuously distributing all said material over said plate and reducing the fibrous material to substantially individualized fibers, whereby the air passing through said plate carries the material including the individualized fibers into suspension therein, conducting the resulting suspension as a continuous stream at superatmospheric pressure to a stationary localized 10 depositing area which is traversed by the surface of a cylindrical fiber-felting screen rotating on a substantially horizontal axis, applying sub-atmospheric pressure to the underside of said screen at said depositing area in a manner to draw through said screen all the air of said suspension and tending to draw in air from the surrounding atmosphere outside of said cylinder, dividing the resulting stream of air and any fines of suspended material drawn through said screen at the depositing area into at least two portions of which one portion contains substantially all of said fines, diverting from the air streams recited the air of said portions which is substantially lacking in fines, combining said fines with said first-mentioned fibrous material to recycle the fines, applying a continuously moving web of sheet material over the felt already formed on said cylinder and at a location removed from said depositing area for travel of the web with the cylinder in facial engagement with the felt thereon and for supporting the felt, and removing the web and the felt from the cylinder.

6. The method which comprises continuously feeding material including fibrous material into a continuous stream of air, conducting the mixed air and all said material to a perforated dispersing plate for passage of the air therethrough, continuously distributing all said material over said plate and reducing the fibrous material to substantially individualized fibers, whereby the air passing through said plate carries the individualized fibers into suspension therein, directing the resulting suspension at superatmospheric pressure at a stationary localized depositing area which is traversed by the top side of a cylindrical fiber-felting screen rotating on a substantially horizontal axis, applying sub-atmospheric pressure to the underside of said screen at said depositing area in a manner to draw through said screen all the air of said suspension and tending to draw in air from the surrounding atmosphere outside of said cylinder, dividing the air and any fines of suspended material drawn through said screen at the depositing area into at least two portions of which one portion contains substantially all of said fines, diverting from the air streams recited the air of said portions which is substantially lacking in fines, combining said fines with said first-mentioned fibrous material to recycle the fines, applying a continuously moving web of sheet material over the felt already formed on said cylinder near the top region of the cylinder and at a location removed from said depositing area for travel of the web with the cylinder in facial engagement with the felt thereon, and at a region where said web underlies said felt in position to support the felt removing the felt and web from the cylinder for vehicular support of the felt by the web.

7. Apparatus for dry felting comprising in combination, feeding means for continuously supplying dry fibrous material at a uniform rate, fiber dispersing means arranged to receive said fibrous material and operable to distribute substantially individualized fibers therefrom into a moving constant current of air at superatmospheric pressure, means open to the atmosphere for continuously admitting fiber-free air to meet infeeding fiber as at least a portion of the air forming said current of air, said current moving to a deposition area, a hollow cylinder rotatable on a horizontal axis and having felting screen area at its periphery arranged to move across said area of deposition, the screen area of the cylinder being

sufficiently extensive to permit continuous passage of all the air of said current through the screen, a stationary suction box for operation at subatmospheric pressure within said cylinder opening to the screen over an area 5 including said deposition area, blower means with a suction intake connected to said suction box for operation to move at least all the air constituting said current, means connected to the outlet of said blower means to free a portion of the air therefrom from fines of material suspended therein, and means to discharge said fines-free air to the atmosphere.

8. Apparatus for dry felting comprising in combination, feeding means for continuously supplying dry fibrous material at a uniform rate, fiber dispersing means arranged to receive said fibrous material and operable to distribute substantially individualized fibers therefrom into a moving constant current of air at superatmospheric pressure continuously drawn in part at least from the atmosphere, said current moving to an area of deposition, 15 a hollow cylinder rotatable on a horizontal axis and having felting screen area at its periphery arranged to move across said area of deposition, the screen area of the cylinder being sufficiently extensive to permit continuous passage of all the air of said current through the screen, a stationary suction box for operation at subatmospheric pressure within said cylinder opening to the screen over an area including said deposition area, blower means with a suction intake connected to said suction box for operation to move at least all the air constituting 20 said current, said blower means having its outlet arranged to discharge at least a part of the air to the atmosphere, a separating cyclone having a receiving opening for an air-suspension of solids for separating it into a stream of air substantially free from said solids and a second fraction containing substantially all said solids, said cyclone being arranged to discharge said second fraction into the said dispersing means for recirculation of said solids and being further arranged to divert said solids-free stream of air from the apparatus, and conduit 25 means connecting the output side of said blower to the receiving opening of said cyclone.

9. Apparatus for dry felting comprising in combination, feeding means for continuously supplying dry fibrous material at a uniform rate, fiber dispersing means arranged to receive said fibrous material and operable to distribute substantially individualized fibers therefrom into a moving constant current of air at superatmospheric pressure continuously drawn in part at least from the atmosphere, said current moving to an area of deposition, 30 a hollow cylinder rotatable on a horizontal axis and having felting screen area at its periphery arranged to move across said area of deposition, the screen area of the cylinder being sufficiently extensive to permit continuous passage of all the air of said current through the screen, a stationary suction box for operation at subatmospheric pressure within said cylinder opening to the screen over an area including said deposition area, blower means with a suction intake connected to said suction box for operation to move at least all the air constituting 35 said current, said blower means having its outlet arranged to discharge at least a part of the air to the atmosphere, a separating cyclone having a receiving opening for an air-suspension of solids for separating it into a stream of air substantially free from said solids and a second fraction containing substantially all said solids, said cyclone being arranged to discharge said second fraction into the said dispersing means for recirculation of said solids and being further arranged to divert said solids-free stream of air from the apparatus, and conduit 40 means connecting the output side of said blower to the receiving opening of said cyclone.

10. Apparatus for dry felting comprising in combination, feeding means for continuously supplying dry fibrous material at a uniform rate, fiber dispersing means arranged to receive said fibrous material and operable to distribute substantially individualized fibers therefrom into a moving constant current of air at superatmospheric pressure continuously drawn in part at least from the atmosphere, said current moving to an area of deposition, 45 a hollow cylinder rotatable on a horizontal axis and having felting screen area at its periphery arranged to move across said area of deposition, the screen area of the cylinder being sufficiently extensive to permit continuous passage of all the air of said current through the screen, a stationary suction box for operation at subatmospheric pressure within said cylinder opening to the screen over an area including said deposition area, blower means with a suction intake connected to said suction box for operation to move at least all the air constituting 50 said current, said blower means having its outlet arranged to discharge at least a part of the air to the atmosphere, a separating cyclone having a receiving opening for an air-suspension of solids for separating it into a stream of air substantially free from said solids and a second fraction containing substantially all said solids, said cyclone being arranged to discharge said second fraction into the said dispersing means for recirculation of said solids and being further arranged to divert said solids-free stream of air from the apparatus, and conduit 55 means connecting the output side of said blower to the receiving opening of said cyclone, a supply of sheet material arranged to move in the same direction as the deposited felt on the cylinder, and means to feed said sheet onto the fiber felt already formed on the cylinder and at a

location removed from said deposition area for facial engagement and travel with the felt.

10. Apparatus for dry felting comprising in combination, feeding means for continuously supplying dry fibrous material at a uniform rate, fiber dispersing means arranged to receive said fibrous material and operable to distribute substantially individualized fibers therefrom into a moving constant current of air at superatmospheric pressure, means open to the atmosphere for continuously admitting fiber-free air to meet infeeding fiber as at least a portion of the air forming said current of air, said current moving to a deposition area, a movable foraminous felting member exposed to atmospheric pressure at regions bounding said deposition area and arranged to move continuously through said deposition area for filtering fiber as a felt thereon from said current of air, a stationary suction box on the non-felting side of said member for operation at subatmospheric pressure opening to said member at an area including said regions and said deposition area, blower means with a suction intake connected to said suction box for operation to move at least all the air constituting said current, means connected to the outlet of said blower means to free a portion of the air therefrom from fines of material suspended therein, and means to discharge said fines-free air to the atmosphere.

11. The method which comprises continuously moving a foraminous felting member exposed to atmospheric pressure at fixed regions bounding a deposition area for filtering fiber as a felt thereon from a suspension of fibers in air exposed to said member at said deposition area, continuously drawing air through said member at said deposition area from the felting side of the member and at said regions from the atmosphere by establishing subatmospheric pressure at said depositing area and the areas of said bounding regions on the other side of said member, directing upon said member at said deposition area a stream of air at superatmospheric pressure containing in suspension material including feltable fibers for felting on said member, the amount of air moving in said stream being less than the amount of air being drawn through said member thereby to prevent escape of suspended material from said stream to the atmosphere, whereby a felt is formed in and removed from said deposition area, removing entrained solids from at least as much air as is in excess of that drawn from the depositing region, and returning at least the solids of the remainder through a region of atmospheric pressure to the suspension of said feltable fibers.

12. Apparatus for dry felting comprising in combination feeding means for continuously supplying dry fibrous material at a uniform rate, fiber dispersing means arranged to receive said fibrous material and operable to distribute substantially individualized fibers therefrom into a moving constant current of air at superatmospheric pressure, means open to the atmosphere for continuously admitting fiber-free air to meet infeeding fiber as at least a portion of the air forming said current of air, said current moving to a deposition area, a movable foraminous felting member exposed to atmospheric pressure at regions bounding said deposition area and arranged to move continuously through said deposition area for filtering fiber as a felt thereon from said current of air, a stationary suction box on the non-felting side of said member for operation at subatmospheric pressure opening to said member at an area including said bounding regions and said deposition area, blower means with a suction intake connection to said suction box, means for operation of said blower to move all the air constituting said current and air from the atmosphere through said bounding regions, means connected to the outlet of said blower means to free a portion of the air therefrom from fines of material suspended therein, and means to discharge said fines-free air to the atmosphere.

13. The method of making a uniform fibrous web comprising the steps of maintaining an excess of separated air entrained fibers on one side of a foraminous surface and with the air under positive pressure whereby both fibers and air are caused to pass in substantially uniform concentrations through the foramen, drawing air through and said fibers onto a moving surface having relatively small foramen by maintaining a pressure below atmosphere on the outgoing side thereof whereby the fibers are deposited on the ingoing side as an interfelted mass, and maintaining the space between the surfaces partitioned from the atmosphere, the air drawn through said moving surface consisting of a minor fraction from the atmosphere and a major fraction comprising all the air from the foraminous surface, whereby a slight inflow of air occurs from the surrounding atmosphere into and through the moving surface to prevent fibers from being blown out into the atmosphere.

14. The method of making a uniform fibrous web comprising the steps of maintaining an excess of dispersed material including essentially separated air entrained feltable fibers on one side of a foraminous surface and with the air under positive pressure whereby both fibers and air are caused to pass in substantially uniform concentrations through the foramen, drawing air through and said fibers onto a moving surface having relatively small foramen by maintaining a pressure below atmosphere on the outgoing side thereof whereby the fibers are deposited on the ingoing side as an interfelted mass, maintaining the space between the surfaces partitioned from the atmosphere, the air drawn through said moving surface consisting of a minor fraction from the atmosphere and a major fraction comprising all the air from the foraminous surface, whereby a slight inflow of air occurs from the surrounding atmosphere into and through the moving surface to prevent fibers from being blown out into the atmosphere, dividing the material passing through said moving surface into the region of subatmospheric pressure on said outgoing side into an air fraction and a residue, and discharging the air fraction to the atmosphere.

15. The method of making a uniform fibrous web comprising the steps of maintaining an excess of dispersed material including essentially separated air entrained feltable fibers on one side of a foraminous surface and with the air under positive pressure whereby both fibers and air are caused to pass in substantially uniform concentrations through the foramen, drawing air through and said fibers onto a moving surface having relatively small foramen by maintaining a pressure below atmosphere on the outgoing side thereof whereby the fibers are deposited on the ingoing side as an interfelted mass, maintaining the space between the surfaces partitioned from the atmosphere, the air drawn through said moving surface consisting of a minor fraction from the atmosphere and a major fraction comprising all the air from the foraminous surface, whereby a slight inflow of air occurs from the surrounding atmosphere into and through the moving surface to prevent fibers from being blown out into the atmosphere, dividing the material passing through said moving surface into the region of subatmospheric pressure on said outgoing side into an air fraction and a residue, and discharging the air fraction to the atmosphere.

16. The method of making a uniform fibrous web comprising the steps of maintaining an excess of dispersed material including essentially separated air entrained feltable fibers on one side of a foraminous surface and with the air under positive pressure whereby both fibers and air are caused to pass in substantially uniform concentrations through the foramen, drawing air through and said fibers onto a moving surface having relatively small foramen by maintaining a pressure below atmosphere on the outgoing side thereof whereby the fibers are deposited on the ingoing side as an interfelted mass, maintaining the space between the surfaces partitioned from the atmosphere, the air drawn through said moving surface consisting of a minor fraction from the atmosphere and a major fraction comprising all the air from the foraminous surface, whereby a slight inflow of air occurs from the surrounding atmosphere into and through the moving surface to prevent fibers from being blown out into the atmosphere, dividing the material passing through said moving surface into the region of subatmospheric pressure on said outgoing side into an air fraction and a residue, said air fraction consisting of an amount of air at least equal to the amount being drawn through the moving surface from the atmosphere, discharging the air fraction to the atmosphere, and feeding said residue to the positive-pressure side of said foraminous surface.

UNITED STATES PATENT OFFICE
CERTIFICATE OF CORRECTION

Patent No. 2,940,133

June 14, 1960

Clark C. Heritage

It is hereby certified that error appears in the printed specification of the above numbered patent requiring correction and that the said Letters Patent should read as corrected below.

Column 3, line 31, for "on", first occurrence, read
-- or --; column 8, lines 69 and 70, for "combined" read
-- combining --.

Signed and sealed this 29th day of November 1960.
